William J. Hampton, South Euclid, Ohio, assignor to Addressograph-Multigraph Corporation, Cleveland, Ohio, a corporation of Delaware

Application September 26, 1955, Serial No. 536,553

1 Claim. (Cl. 101—336)

This invention relates to printing machines and more particularly to printing machines that utilize a ribbon for producing impressions.

As is well known, printing machines which utilize a ribbon cooperating with a printing plate to produce impressions usually embody a ribbon reversing means for reversing the direction of ribbon feed when the supply spool or the like for the ribbon is exhausted, and the primary object of the present invention is a ribbon reversing means adapted to operate on a relatively simple principle and one which includes a minimum of actuating structure responsive to the exhaustion of the means supplying the ribbon. Specifically, the object of the invention is to utilize a feed lever having alternate fulcrums enabling feed means on the lever to be alternately operative. When the tension on the ribbon is excessive, as where the ribbon is exhausted on the supply spool, means are then effective to shift the fulcrum and this movement in turn is effective to disable the one feed means on the feed lever and to dispose the other feed means in operative position.

Heretofore, the ribbon for printing has usually taken the form in most instances of a woven fabric ribbon such that the discontinuous pattern or weave of the ribbon is perceptible in the impressions produced, and this is deemed objectionable where it is desired to obtain impressions comparable to that obtained from letter-press printing. A further object of the invention is to enable solid, that is, uniformly continuous, character impressions to be made from a ribbon, and specifically to produce such characters from a carbon-faced ribbon in contrast to a fabric ribbon impregnated with ink. A carbon ribbon may be prepared by coating a narrow tough web of tissue paper with carbon duplicating material of any known kind. Paper of this kind is of course fine-textured in contrast to the coarse weave of a fabric ribbon, and being coated rather than impregnated with duplicating material impressions taken therefrom will be uniformly solid and not broken.

Other and further objects of the present invention will be apparent from the following description and claim and are illustrated in the accompanying drawings which by way of illustration, show preferred embodiments of the present invention and the principles thereof and what I now consider to be the best mode in which I have contemplated applying these principles. Other embodiments of the invention embodying the same or equivalent principles may be used and structural changes may be made as desired by those skilled in the art without departing from the present invention and the purview of the appended claim.

In the drawings:

Fig. 1 is a side elevational view of a hand operated printing machine embodying the features of the present invention;

Fig. 2 is a front elevational view of the machine as shown in Fig. 1;

Fig. 3 is a top plan view of the machine as shown in

2

Fig. 1, this view being partly in section along the line 3—3 of Fig. 1;

Fig. 4 is a side elevational view of the side of the machine opposite that shown in Fig. 1;

Fig. 4A is a plan view of a printing device;

Fig. 4B is an end elevation of the printing device shown in Fig. 4A;

Fig. 5 is an elevational view, partly in section, taken just rearwardly of the printing anvil as in Fig. 8 and looking in a forward direction;

Fig. 6 is a detail view taken on the line 6—6 of Fig. 7 so as to show the opposite side of certain parts appearing in Fig. 5;

Fig. 7 is a sectional view taken on the line 7—7 of Fig. 5;

Fig. 8 is a sectional view taken on the line 8—8 of Fig. 1;

Fig. 9 is a detail of the take-up spool;

Fig. 10 is a plan view, part in section, of the take-up spool and certain means associated therewith;

Fig. 11 is a sectional view taken on the line 11—11 of Fig. 10; and

Figs. 12 and 13 are perspective views, respectively of the supply spool and the ribbon clamp associated therewith.

General description

The present invention is herein illustrated as embodied in a hand operated printing machine 20, Fig. 1, of the kind illustrated in the co-pending application Ser. No. 445,771, filed July 26, 1954. This printing machine is adapted to utilize printing devices D of the kind shown in Fig. 4A, but the printing device D is only exemplary of a printing device removably carrying a printing plate

35 formed with embossures for printing. Thus, the printing device D embodies a frame 25 on which is disposed a flat metallic printing plate 26 having embossed type characters 26T formed thereon, and it will be observed that such type characters are of reverse reading style so as to cooperate with a carbon-faced imprinting ribbon 40 during printing from the embossures 26T as will be described.

In the upper area or portion of the printing device D, an index card 27 is removably retained, and this index card carries an impression 27P from the plate 26 for readily identifying the printing plate 26.

The printing machine 20 in this instance embodies a relatively rigid and stable base structure supporting at the rear end of the machine an upstanding magazine 30, Figs. 1 and 4, in which the printing devices D are adapted to be stacked one on the other, and during the course of operation of the machine the printing devices D are advanced by feed means one by one from the bottom of the magazine 30 forwardly along a guideway in the machine to a printing station 32, Fig. 1, and from the printing station 32 in to a collecting magazine 36 which is disposed at the front of the machine below the plane of the printing station.

The supply magazine 30 is formed of opposed sheet metal stampings 30L and 30R, Fig. 3, which include front and rear portions of the printing devices D stacked therein so that the corner embracing flanges in each member 30L and 30R are spaced apart in a front to rear direction the width of device D.

65 Forward feeding of the printing devices occurs as an incident to repeated raising and lowering of a platen lever 37 which supports a stamper platen 38 of the usual kind. The platen lever 37, as will be observed in Fig. 2, is in the form of a yoke including rearwardly extending arms 37L and 37R, and at the forward end the lever 37 is provided with a handle H. In the present instance, a carbon ribbon CR, Figs. 1, 3 and 4, is stretched trans-

70

versely across the printing station 32 so as to be directly beneath the platen 38 in lowered position, and the carbon face of the ribbon faces upwardly. A printing device as D when at the printing station 32 underlies the carbon ribbon with the embossed characters 26T thereof disposed upwardly. Consequently, the sheet to be printed, which will be disposed over the printing station 32 so as to overlay the carbon ribbon CR, will be imprinted on the downwardly disposed face thereof by the type characters 26T underlying the carbon ribbon CR when the platen 38 is brought to bear upon the upwardly disposed face of the sheet to be printed.

As shown in Fig. 3, the rear ends of the arms 37L and 37R of the platen lever 37 are pivoted on pins 39 and 40 supported in a way to be described. When the platen lever is lowered, this is accomplished in opposition to a relatively strong spring 37S, Fig. 4, which normally holds the platen lever 37 in an elevated position, and operation of the lever 37 also controls feeding of the ribbon CR, as will be described.

Inasmuch as the way in which the printing devices D are advanced to printing position from the magazine 30 is described in detail in the aforesaid co-pending application, the manner in which this is accomplished need not be redescribed herein, but it is important to point out that the printing devices during the course of forward movement through the machine are guided by rails that are in part supported by a pair of spaced apart mounting blocks 41L and 41R, Figs. 4 and 8, which are held in spaced relation by means including a rigid spacer bar 42, Fig. 3, secured at either end to the inner faces of the mounting blocks 41L and 41R as by cap screws 42S, Fig. 3. In like manner, a printing anvil A, Figs. 1 and 3, is extended between the mounting blocks 41L and 41R, and this anvil lies beneath the carbon ribbon CR and serves to back up the printing device as D during the printing operation.

As described with particularity in the aforesaid co-pending application, the printing devices are advanced through the machine by carrier bars or feed dogs, and these carrier bars are indicated at 43 in Fig. 8 hereof. The carrier bars 43 are arranged for longitudinal reciprocation on shoulders 41S of the mounting blocks 41L and 41R, and are confined for such movement by retainer plates 44 that are secured to the inner faces of the mounting blocks. The upper edges of the plates 44 are formed with guide flanges 44F that are spaced inwardly from the upper edges of the carrier bars 43 thereby to afford rail elements for bottom ribs 25R, Fig. 4B, that are formed at either side edge of the printing device D.

In affording standards for the machine, rear leg structure is provided in the form of a relatively heavy bar 45, Figs. 1 and 4. This bar is U-shaped in vertical cross section, and thus includes vertical spaced apart arms which are adapted, respectively, to be secured to the inner faces of the mounting blocks 41L and 41R adjacent the supply magazine 30 as by cap screws 46 and 47 in each instance. These arms at the upper ends 45E thereof, Fig. 3, serve as rigid bearing supports for the pins 39 and 40 on which the platen lever 37 is pivoted. The lower or bight portion of the member 45 is provided with a resilient pad or foot 45P for engaging the surface upon which the machine is to be supported.

The collecting magazine 36 serves in part to provide forward leg structure. In this connection, it will be observed first that the magazine 36 is formed to include a pair of parallel spaced apart sheet metal side members 36L and 36R, Fig. 3, having in-turned forward ends 36F which are adapted to engage the leading edges of the printing plates advanced in to the magazine 36 from printing position, the members 36L and 36R being spaced apart a distance corresponding to the width of a printing device D.

The collector magazine 36 as thus afforded is an

chored to the forward face of the printing anvil A by cap screws as 52, Figs. 2 and 3. The upper end of the collector magazine 36 is disposed primarily beneath the level of the printing device guideway of the machine, 5 as described in the aforesaid co-pending application, thereby to allow the printing devices to be fed forwardly from printing position on the anvil A so as to fall printing-face-up into the open cavity of the collecting hopper 36 and onto a yieldable bottom support 55 therein.

Across the bottom of the collecting magazine 36, a relatively heavy cross member 60, Figs. 2 and 4, is disposed, and this cross member is secured as by welding to the lower face of a horizontal bottom flange 51B, Fig. 3, extending forwardly from the lower edge of the rear plate 51 of the magazine 36. The cross bar 60 has resilient pads 60P, Fig. 4, secured to the bottom face thereof, these being in the nature of the pad 45P described above.

The printing station

The printing station 32, Fig. 1, is constituted primarily by the carbon ribbon CR and the printing anvil A. Reference was made above to the plates 44 having flanges 44F that serve to guide the printing devices D advanced forwardly from the supply magazine 30. It will be observed in Fig. 3 that these flanges 44F terminate short of the rear end of the printing anvil A, and it will be further observed in Fig. 5 that the printing anvil A is grooved 30 at 70 either side edge thereof. The lateral spacing between the grooves 70 thus provided in the printing anvil A corresponds to the lateral spacing of the flanges 44F so that when a printing device as D attains printing position, the ribs 25R thereof will be disposed in the 35 grooves 70 and the lower face of the printing device will rest flush on and be supported by the upper surface 71, Fig. 5, of the printing anvil A. A pair of relatively narrow, elongated retaining plates 73 and 74 are secured to the upper edges of the mounting bars 41L and 41R, 40 as shown in Fig. 3, so as to prevent upward displacement of the printing devices while being advanced in the direction of the printing anvil A, and these retainers extend from just forwardly of the supply magazine 30 to beyond the printing anvil A.

A ribbon guard 75, Fig. 3, is disposed over the anvil A. The guard 75 includes an opening 75W through which is visible the index card as 27 on a printing device D disposed in printing position on the anvil A. Forwardly of the opening 75W and in the portion that is directly over the anvil A, the ribbon guard is provided with a relatively large U-shaped recess 75R, Fig. 3, and it is the recess which enables the platen 38 to cooperate with the ribbon CR to produce the desired impressions.

The carbon ribbon feed

Under the present invention, a carbon ribbon CR is arranged to traverse the printing station 32 in a step by step fashion as an incident to each positive operation of the platen lever 37, and the way in which this is accomplished will be explained after the supporting spools for the carbon ribbon have been described.

As shown in Fig. 3, a pair of ribbon spools 80L and 80R are arranged on opposite sides of the machine, and the mounting means utilized in this connection are in the form of U-shaped brackets 81L and 81R, Fig. 3, having the web or bight portions thereof fastened by cap screws 82 to the outer faces of the corresponding mounting blocks 41L and 41R. The same cap screws, it will be observed, also serve to secure the printing anvil A to the inner faces of the mounting blocks 41L and 41R. The spools 80L and 80R are adapted to be separately driven by means including respective ratchet wheels 84L and 84R, Fig. 3, and the operation of such will be described below in connection with the ribbon reversing means.

The brackets 81L and 81R, in addition to supporting the ribbon spool means, also support a pair of freely rotatable ribbon guide rollers 86L and 86R, Figs. 2 and 3. The ribbon guides 86L and 86R are formed at either end with reduced shaft portions as 88 in each instance, and these shaft portions are respectively provided with short journal pins 89 and 90 which are engaged in suitable openings provided in the opposite arms of each bracket 81L and 81R.

The foregoing arrangement of the ribbon spools and guides is such that the carbon ribbon is disposed to travel at an angle across the printing station. By thus canting the path of the ribbon, fresh portions of the ribbon will be presented to the embossures on successive ones of the printing plates arriving at the printing station, which is to say that the ribbon is out of parallel with respect to the lines of embossed characters 26T.

Inasmuch as the spools 80L and 80R are of different construction and are supported somewhat differently in each instance, the two spool arrangements will be treated separately herein. Considering first the spool 80L, it will be observed that this spool is provided with an amount of the ribbon CR. Under the circumstances illustrated, as will be more apparent from the description to follow, the spool 80L is a take-up spool, so that this spool is the one that is driven while the spool 80R is idled as a supply spool. As will be described in more detail below, when the supply spool 80R is exhausted, ribbon reversing means are thereupon operative to reverse the direction of feed so that the take-up and supply relation between the spools 80L and 80R is reversed.

The spool 80L may be of plastic or the like and is provided with a segmental sheet metal spring clamp 93, Figs. 9 and 10. The clamp is separable and thus includes an end 93E that engages in a notch 90N formed in the outer periphery of the spool 80L, and the end portion of the ribbon CR on the spool 80L is clamped between the outer periphery of the spool and the inner face of the spring clamp 93.

The drive ratchet 84L for the take-up spool 80L is fast on a drive shaft which includes a boss 95, Fig. 10, having a reduced end portion 95E that fits into the central or axial opening in the spool 80L. The drive shaft 95 is formed with a pair of opposed drive dogs 95D. These opposed drive dogs are adapted to drivingly engage in a corresponding opposed pair of a plurality of grooves 97 formed radially about the inner diameter of the spool 80L, and the grooves 97 extend from one end of the spool to the other as will be clear from Fig. 10. As a consequence, step-wise rotary motion imparted to the ratchet 84L will in turn be imparted to the take-up spool 80L so as to withdraw a predetermined amount of ribbon from the supply spool 80R.

Rearwardly of the ratchet wheel 84L, the drive shaft 95 is formed with a reduced portion 98, Fig. 3, which extends through an opening in the rear arm of the supporting bracket 81L. A sleeve 100, Fig. 3, including a pair of spaced apart flanges 101 and 102 of enlarged diameter, is secured as by a set screw 103 to the reduced end portion 98 of the drive shaft 95, and interposed between the disk 102 and the rear arm of the mounting bracket 81L is a spacer bushing 105 that is carried in an opening in the rear arm of the bracket. The sleeve 100 in the portion between the disks 101 and 102 is clamped by a pair of segmental brake shoes 106 and 107, Fig. 8. The segmental brake shoes thus afforded include inwardly extending arms as 108, and the ends of these arms embrace opposite sides of a pin 110 which is fastened to the rear arm of the mounting bracket 81L so as to extend rearwardly thereof as shown in Fig. 3. An adjusting screw 112, Fig. 8, is threadedly mounted in the arms as 108 on the side of the pin 110 that is nearer the spool 80L, and interposed between the cap of this screw and the under side of the arm 108 for the lower shoe 106 is a relatively strong coil spring 115 which is adapted to place

the shoes 106 and 107 under a selected amount of tension determined by adjustment of the screw 112. In this way, the degree of tension or slack of the carbon ribbon while being fed may be determined.

5 The spool 80L at the end opposite the drive shaft 95 is supported in part by a relatively long idler shaft 115, Fig. 3, which is passed through a bushing 116 mounted in the forward arm of the mounting bracket 81L. At its inner end, the idler shaft 115 carries a bushing 118, Figs. 9 and 10, that is adapted to fit the open end of the spool 80L opposite the drive shaft 95. A pin 120, Fig. 9, is passed through aligned openings in the inner end of the idler shaft 115 and the bushing 118, and opposite ends of this pin project beyond the bushing 118 to engage in a pair of 15 grooves 97 in the spool 80L so that the bushing 118 and the idler shaft 115 will turn with spool. The bushing 118 at the outer end is formed with an enlarged flange 121, and a relatively strong coil spring 122 concentric to the idler shaft 115 is interposed between the flange 121 and the forward arm of the mounting bracket 81L, as shown in Fig. 3. This coil spring serves to hold the spool 80L firmly in driving engagement with the drive dogs 95D of the drive shaft 95.

20 Forwardly of the bushing 116, the idler shaft 115 is provided with a retainer knob 123. A cooperating retainer in the form of a leaf spring 125 is fastened to the outer face of the forward arm of the mounting bracket 81L, and this leaf spring is formed with a portion 125E that projects inwardly with respect to the retainer knob 123, thereby serving to limit outward displacement of the idler shaft 115. However, by retracting the spring retainer 125, the idler shaft 115 may be withdrawn to withdraw the bushing 118 from the spool 80L. To replace a spool as 80L, it is merely necessary to press the 30 spool at the rear end in the direction of the forward arm of the bracket 81L against the action of the spring 122 to relieve the spool from the drive dogs. The outer end of the idler shaft 115 is provided with a kerf 115K so that a screw driver or the like may be used to manually 35 rotate the spool 80L through the pin 120.

The supply spool 80R, Figs. 5 and 12, is in the form of a relatively heavy metal core formed with an axial opening extending therethrough, and a long mounting shaft 130, Fig. 3, is passed through this axial opening 40 in the spool 80R. The mounting shaft 130 thus provided is of sufficient length to project forwardly beyond the forward arm of the mounting bracket 81R, and at this end is kerfed at 130K for the purpose mentioned above in connection with the shaft 115. The shaft 130 projects 45 rearwardly beyond the rear arm of the mounting bracket 81R, and a braking sleeve 100A identical to the sleeve 100 described above is mounted on the projecting rear end portion of the shaft 130. Similarly, shoes 106A, Fig. 8, clamp the sleeve 100A, and since this arrangement 50 operates like the brake for the spool 80L, such need not be redescribed.

The ratchet wheel 84R in this instance is fast on the spool 80R, and a portion of the spool 80R projects rearwardly beyond the ratchet 84R so as to afford a spacer bushing 132, Fig. 3, interposed between the ratchet wheel 84R and the rear arm of the bracket 81R.

The spool 80R is provided with a slot 80S, Fig. 5, through which an end of the ribbon CR may be passed. A split sleeve 135, Fig. 13, is adapted to be pressed on to 60 the spool 80R, and this sleeve is formed with radial projecting ears 135E which, when the sleeve 135 is on the spool 80R, abut the forward side of the ratchet 84R as shown in Fig. 3. The sleeve 135 is provided with a slot 135S through which the aforementioned end of the ribbon CR is adapted to be passed. The sleeve 135 is split at 136, and the width of the split is such as to expose both ends of the slot 80S when the sleeve 135 is on the spool. The sleeve 135 is turned on the spool until the slot 135S along one split edge thereon registers with 70 one end of a pressure pin 138 at the end of the spool 75

opposite the ratchet 84R. Accordingly, by threading the end of the ribbon through the registered slots in the spool and the sleeve, and then by applying a rotative force to the ears as 135E, the sleeve 135 can be turned past and over the pin 138, and the loose end of the ribbon will be securely clamped between the spool 80L and the sleeve 135.

As will be observed from Fig. 3, the two ratchets 84L and 84R are in alignment. To drive one or the other ratchet so as to index the corresponding take-up spool through ribbon advancing movements, a reciprocable feed lever to be described in detail below is afforded. This feed lever is adapted to assume one of two respective tilted positions whereat means thereon drivingly engage whichever of the two ratchet wheels 84L as 84R is the one associated with the take-up spool, and this feed lever is further adapted to reverse the aforesaid two positions when the ribbon on the supply spool is exhausted so that drive means on the feed lever then drivingly engage the spool that was just exhausted to transform this spool into a take-up spool.

Ribbon reversing mechanism

The ribbon spools 80L are arranged to be actuated in a step by step indexing or ribbon advancing movement by means including a reciprocable feed lever or pawl bar 150, Figs. 5, 7 and 8, which is located in a transverse position rearwardly of the printing anvil A, as will be observed particularly in Fig. 7. The feed lever 150 is supported by and actuated with a control lever that is suspended from the rear side of the anvil A. Thus, as shown particularly in Fig. 7, a pivot stud 151 extends rearwardly from the anvil A just below the top surface 71 thereof and at substantially the medial position between the opposite ends of the anvil A as will be apparent from Fig. 3. Pivot on a reduced rearwardly extending portion 151R of the mounting stud 151 is a depending oscillatable control lever 152 which is adapted, as will be described, to reciprocate the feed lever 150 from the position shown in Figs. 5 and 8 to the right through an idle movement, and then back to the position shown in Figs. 5 and 8 with a positive action on the ratchet 84L, for taking-up predetermined amounts of the ribbon on the spool 80L.

The control lever 152 has a vertically slidable bar 153 disposed flush against the rear face thereof, and the upper end of the slide bar 153 is notched at 153N to embrace the remote rear end portion of the mounting stud 151. The notch 153N is relatively deep as will be observed in Fig. 5, and this enables the slide bar 153 to shift vertically with respect to the control lever 152 for a purpose associated with ribbon reversing as will be mentioned. The slide bar 153 is held against the control lever 152 in part by a C-washer 154 that is sprung into a retainer groove of the usual kind that is provided at the rear end of the mounting stud 151.

The slide 153 is formed with an opening in which is disposed a pin 156 having a rearwardly projection portion 157 serving as an anchor for the upper end of a coil spring 158 that is adapted to hold the slide 153 in a normally down position. Thus, the lower end of the coil spring 158 is anchored to a pin 159 that projects rearwardly from the control lever 152. The pin 156 on which the spring 158 is anchored includes a forwardly projecting portion 160, and journaled on this portion of the pin 156 is a cam roller 162 retained in position by a ring and C-washer 163 and 164 respectively. It is this roller which serves in part to produce shifting movement of the lever 150 in one direction when the control slide 152 oscillates.

Substantially in the medial portion, the control lever 152 is provided with an elongated slot 152N, and the portion of the pin 156 which carries the force transmitting roller 162 is disposed in the slot 152N enabling the pin 156 and roller 162 to shift upwardly with respect

to the control lever 152 under circumstances to be described.

As will be observed in Figs. 5 and 6, the roller 162 is adapted to engage an inner side of one or the other of a pair of complementary, generally semi-circular cam surfaces 170 and 171 that are formed in the upper edge of the feed lever 150, and the spring 158 serves to hold the roller 162 firmly down in such relation. These cam surfaces are formed in opposed relation substantially at the mid-point of the feed lever 150 and meet to provide a dead center point or tooth 173.

Above the pin 159, the control lever 152 carries a drive pin 180, and the ends of this pin project beyond the opposite faces of the feed lever 150 and the slide bar 153 as shown in Fig. 7. The lower end of the slide bar 153 is provided with a downwardly opening slot 153N2 that embraces the pin 180, and the upper end of this slot is normally held down on the pin 180 by the spring 158. Ring washers as 181 serve to prevent outward displacement of the pin 180 in the opposite direction, and at the same time these washers serve in effect to hold the feed lever 150 to the control lever 152.

As shown in Figs. 5 and 6, the feed lever 150 in the portion below the dead center point 173 is formed with a generally C-shaped slot 185, and the configuration is such that this slot affords a pair of opposed pockets 185A and 185B that are separated by a downwardly projecting tooth or dead center element 185T directly below the dead center point 173. In the portion that corresponds to the slot 185, the pin 180 is formed with an enlargement 185E which is adapted to be disposed in one or the other of the pockets 185A and 185B, and it is important to point out that the arrangement is such that the pin 180 in part accounts for a tilted condition of the feed lever 150. Thus, it will be observed that the pockets 185A and 185B are displaced to either side of the dead center point 173. The spring 158, as was mentioned, tends to hold the slide bar 153 downwardly to the extent that the upper end of the slot 153N2 engages the pin 180. This arrangement at the same time pulls the roller 162 firmly down against the sloped cam surface 171 just adjacent the dead center point 173, and as a consequence the feed lever 150 tends to be rocked or tilted in a counterclockwise direction as viewed in Figs. 5 and 8 about the enlargement 185E of the drive pin 180 as a fulcrum. This accounts for a drive pin 150A, Fig. 8, being drivingly engaged with the teeth of the ratchet wheel 84L for the take-up spool 80L. Thus it will be seen that the control lever 152 not only carries and drives the feed pawl 150, but it also provides a fulcrum in the form of the pin 180 that enables the feed pawl 150 to assume two different driving positions with respect to the control lever 152. A first such position would be that shown wherein the pin 150A is adapted to drive the ratchet 84L. The second position will be mentioned below.

The condition shown in Figs. 5 through 8 will prevail until repeated return reciprocations of the feed lever 150, accomplished in a way to be described, exhaust the supply spool 80R. When this occurs, the ribbon CR will be taut at the end anchored to the supply spool 80R as illustrated in Fig. 5. Therefore, the drive pin 150A drivingly engaging the ratchet 84L is unable to further turn the takeup spool 84L clockwise as viewed in Fig. 8 so that the feed lever 150 cannot be shifted through a full return movement by the control lever 152. When this condition is encountered, the roller 162, during the time that forces are effective to oscillate the control lever 152 in a return direction, will be caused to travel over the dead center point 173 with a snap action to engage the opposite cam surface 170. This of course is accompanied by an upward forced movement of the roller 162 in the slot 152N, and results at the same time in upward sliding movement of the slide bar 153. This produces disengagement between the upper end of the slot 153N2 and the pin 180, and frees the pin 180 for a shift.

Therefore, as the roller 162 travels to the left as viewed in Fig. 5 over the dead center point 173, which is a forced action as will be described, the pin 180 is at the same time carried along in a left hand direction with the control lever and the slide bar 153, so that the enlargement 185E is transferred from the pocket 185A to the pocket 185B. Thus, after the roller 162 is disposed on the cam surface 170, just to one side of the tooth 173, the enlargement 185E will be disposed in pocket 185B. The fulcrum for the feed lever or pawl bar 150 is thereby shifted to the opposite side of the tooth 173, and the spring 158, acting again on the roller 162 will be effective to again dispose the parts in a normal condition, as in Fig. 7 except in a reversed sense.

The net effect of the foregoing reversal or transposition is to rock or pivot the feed lever 150 in a clockwise direction on the fulcrum pin 180 as viewed in Figs. 5 and 8, so that the drive pin 150A is lowered out of driving engagement with the ratchet wheel 84L. At the same time, a drive pin 150B at the opposite end of the feed lever 150 is elevated to drivingly engage the teeth of the ratchet wheel 84R that is associated with the spool 80R that was just exhausted. Therefore, subsequent oscillations of the control lever 152 and reciprocation of the feed lever 150 will be effective to rotate the spool 80R counterclockwise as viewed in Fig. 8.

Oscillation is imparted to the control lever 152 by a horizontal link 200 which, as shown in Fig. 3, extends inwardly from a point below the mounting bar 41L. At its inner end, the link 200 is formed with a horizontal forwardly projecting end portion 201, and this end portion Fig. 7, extends through an opening at the bottom of the control lever 152 and is retained in position by C-washers as 201C. The opposite end of the drive link 200, that is, the end that is adjacent the mounting block 41L, is formed with an upstanding portion 203, Fig. 1, which engages an opening in one arm 206A of a bell crank lever 206 which is pivoted and retained by a C-washer on the lower end of a stud 207. The upper end of the stud 207 is suitably anchored in the mounting block 41L. The opposite arm 206B, Fig. 3, of the bell crank 206 extends outwardly beyond the mounting block 41L, and a down-turned end 210 of a transmitting link 212 is mounted in an opening in the arm 206B of the aforementioned bell crank and is retained by C-washers. The end of the transmitting link 212 opposite the end that is attached to the bell crank 206 is formed with an inwardly extending portion 213, and this end of the transmitting link 212 is disposed in an opening provided at the lower end of an operating lever 215, Figs. 1 and 2.

As will be observed in Fig. 1, the transmitting lever 215 is disposed outwardly of the mounting block 41L, and the upper end of this lever is bifurcated at 215B, Fig. 1, so as to embrace a drive pin 218 which is fixed to the arm 37L of the platen lever 37 in position above the pivot pin 40 on which the platen lever 37 is arranged to pivot.

It will be recalled that mention was made of the spring 37S, Fig. 1, and it will be observed that this spring is anchored at one end to the lever 215, and at the opposite end this spring is anchored to the rear arm of the mounting bracket 81L for the mechanism associated with the ribbon spool 80L. The spring 37S is effective to dispose the platen lever 37 and the operating lever 214 in the normal position shown in Fig. 1. When, however motion is imparted to the platen lever 37 the pin 218 is effective on the bifurcated end of the lever 215 to oscillate the lever 215 clockwise, as viewed in Fig. 1. As an incident to this, the bell crank 206 is pivoted clockwise, as viewed in Fig. 3, and such pulls the link 200 to the right. Such right hand movement of the link 200 will oscillate the control lever 152 to the right as viewed in Figs. 5 and 8. The feed lever 150 will be shifted with the control lever 152, and this will cause the drive pin 150A to be carried idly over the tooth T-1, Fig. 8, of the ratchet 84L and into

the tooth recess R-1. The feed lever 150 will pivot slightly to enable this to occur, and when the platen lever 37 has been lowered to an effective or printing position, the aforementioned drive pin 150A will then be operatively engaged with the tooth T-1 on the ratchet wheel 84L. Consequently, when the platen lever 37 is released to the return action of the spring 37S, the bell crank 206 will then pivot counterclockwise, as viewed in Fig. 3, to force the link 200 to the left as there viewed. The feed lever 152 is thereupon oscillated clockwise, as viewed in Fig. 8, and a positive clockwise motion is thereupon imparted to the ratchet wheel 84L of the take-up spool.

The foregoing in a reversed sense, that is, when the spool 80R constitutes the take-up spool, will be apparent from the foregoing. Thus, briefly, the drive pin 150B under this circumstance will be operative. When the feed lever 150 first shifts to the right as viewed in Fig. 8, the ratchet 84R will be indexed counterclockwise, and when the lever 150 returns the feed pin 150B will idly move across the next tooth of the ratchet 84R to be drivingly engaged.

Hence, while I have illustrated and described the preferred embodiments of my invention, it is to be understood that these are capable of variation and modification, and I therefore do not wish to be limited to the precise details set forth, but desire to avail myself of such changes and alterations as fall within the purview of the following claim.

I claim:

30 In a printing machine having a printing anvil, a feed and reversing mechanism for a carbon ribbon and comprising a pair of ribbon spools supported outwardly of the respective ends of said anvil and each having a ratchet wheel and a drive shaft connected thereto for advancing said spools, clamping means engaging each of said drive shafts to apply individual retarding forces to said ratchet wheels, means to individually adjust said clamping means to selectively establish the amount of retarding force applied to each of said drive shafts, guide rollers journaled for free rotation outwardly of the ends of said anvil and over which the carbon ribbon passes in passing to and from said spools, a generally vertically disposed control lever pivotally mounted on said anvil and depending therefrom, a generally horizontal feed lever disposed in a plane between the upper and lower ends of said control lever and having drive means at opposite ends for respectively drivingly engaging one of said ratchet wheels when said feed lever is in a first tilted generally horizontal ratchet driving position and for drivingly engaging the other of 40 said ratchet wheels when in a second tilted generally horizontal ratchet driving position, said feed lever having opposed upper and lower edges and being formed with an opening substantially at its midpoint affording a pair of symmetrical fulcrum pockets disposed between the upper and lower opposed edges of said feed lever, said feed lever having a tooth formed on the periphery of said opening between said pockets, said tooth pointing downward toward the lower edge of said feed lever, said feed lever having another tooth formed on the upper one of said opposed edges thereof and whereat ends of a pair of symmetrical cam surfaces terminate, said cam surfaces also being formed on said upper edge of the feed lever, said teeth being directly opposite one another and said pockets and said cam surfaces being spaced substantially equally 50 between the center points of said teeth, a supporting and driving pin fixed on said control lever and being normally disposed in one of said pockets as the sole support for said feed lever and for imparting lateral shifting forces to the first named tooth to move said feed lever laterally upon oscillating movements of said control lever, a second pin normally engaged with one of said cam surfaces, said second pin being fixed on a generally vertically disposed slide bar aligned axially with said control lever, said slide bar being carried on said control lever for movement there-

11

with as a unit and said slide bar being adapted to slide axially relative to said control lever to enable said second pin to be relieved from said one cam surface, a relatively short coil spring anchored at one end adjacent the lower end of said control lever and connected at its other end to the second one of said pins to normally hold the second pin carried by the slide bar forcefully against said one cam surface causing said feed lever to fulcrum about the first pin disposed in one of said pockets as aforesaid, whereby when said feed lever encounters resistance against lateral movement as aforesaid both said pins shift laterally to their second positions to establish a new fulcrum for said

5

12

feed lever causing the feed lever to assume its second tilted position, and drive means connected to the lower end of said control lever below said anchor for said coil spring and below the lower edge of said feed lever and adapted to oscillate said control lever.
